GEORGE BRANCH, OF DELANO, CALIFORNIA

BABBITTING JIG

Application filed July 7, 1928. Serial No. 291,064.

This invention relates to a device for babbitt bearings and especially to one for casting the babbitt in the caps of connecting rods, main bearings and similar parts of gas engines and other machinery.

The principal object of my invention is to provide a jig for this purpose so constructed that the cap to be babbitted may be rigidly and quickly clamped in position on the jig in such a manner that the babbitt when poured is properly centered in the cap and will have the proper thickness and general form desired.

A further object of this invention is to arrange the structure so that merely by interchanging a few simple parts, caps of any dimensions within the usual range may be handled with equal facility.

A further object of the invention is to produce a simple and inexpensive device and yet one which will be exceedingly effective for the purpose for which it is designed.

These objects I accomplish by means of such a structure and relative arrangement of parts as will fully appear by a perusal of the following specification and claims.

In the drawings similar characters of reference indicate corresponding parts in the several views:

30 Fig. 1 is a sectional elevation of my improved jig showing cap to be babbitted in place on the jig but not clamped.

Fig. 2 is a similar view of the cap as clamped and the babbitt poured.

35 Fig. 3 is a sectional plan taken on the line 3-3 of Fig. 2.

Fig. 4 is a perspective view of a symmetrical fillet size controlling ring.

Referring now more particularly to the 40 characters of reference on the drawings, the frame of the jig comprises a vertical plate 1 having a horizontal extension 2 projecting from one side thereof intermediate its ends, said extension being adapted to rest on and be secured to a work bench or the like.

45 Adapted to abut against the front face of the plate 1 is a semi-circular mandrel 3 of suitable length, which is provided with locating dowel pins 4 to seat in the plate and 50 with a stud bolt 5 whereby the mandrel may

be removably but rigidly secured to said plate. The diameter of the mandrel corresponds to the diameter of the shaft to cooperate with the bearing cap, and a number of different sizes of mandrel, all interchangeable, are provided 55 so that the jig may be used for casting bearings for use on any ordinary sized shaft.

The cap 6 to be babbitted straddles the mandrel and also rests against the plate 1. Such caps, as usual, have transversely spaced bolt holes 7, and these holes are utilized to centralize the cap relative to the mandrel and to secure the cap in place by the following means. Journaled in the plate 1 and also in lugs 8 projecting upwardly from the outer end of the frame member 2 are transversely spaced horizontal rods 9, having bosses 10 in front of the plate 1 through which horizontal pins 11 are transversely slidable. These pins are graduated as at 12 and are held at any position in the bosses by set screws 13. From the adjacent ends of the pins tapered nubs 14 project toward the plate 1 so as to enter the bolt holes 7. These pins are initially set in the bosses so that the distance between the nubs is the same distance as that between the bolt holes, which distance is of course known. The graduations on the pins are so numbered that when both pins are set at the same points relative to their respective bosses, the nubs 70 will be then equi-distant from the center line of the mandrel.

When the nubs are frictionally engaged with the bolt holes, therefore, the cap will be centralized relative to the mandrel as will be 75 evident.

The nubs are thus moved into engagement with the bolt holes by the following means. At their rear ends the rods 9 are connected by a cross bar 15. Slidable through this cross 80 bar is a rod 16, which at its forward end is connected to a crank arm 17 projecting from a transverse shaft 18, journaled on the member 2. A radially extending operating handle 19 is connected to one end of the shaft 18 to 85 one side of the frame, so as to enable said shaft to be easily rotated. A compression spring 20 disposed about the rod 16 bears at one end against the cross bar and at the other end against a collar 21 fixed on the rod between 90 95 100

the bar and crank. It will, therefore, be seen that if the handle is turned in a direction so as to push the rod rearwardly through the cross bar, the resistance of the spring will cause the rods 9 and the parts connected thereto, to be moved rearwardly until the nubs frictionally engage the bolt holes. Further movement of the handle in the same direction will then compress the spring so that the nubs will press the cap firmly against the plate 1. The handle is turned until the crank engages a projection 22 on the plate 2, as shown in Fig. 2, at which point the crank is past dead center and the spring cannot act to retract the nubs. The bore of the cap is thus concentric with and spaced from the mandrel, the size of the latter relative to the bore being such as to give the desired thickness of babbitt.

20 The ends of the cap are then closed in to form a pouring chamber for the babbitt by means of the following arrangement. Slidable on the mandrel on both sides of the cap are semi-circular sleeves 23, a pair of which 25 is provided for each mandrel so as to match with the same.

The sleeves at their adjacent ends have enlarged heads 24 which are of greater radius than the cap 6, said heads being recessed to a 30 depth equal to the desired projection of the babbitt beyond the ends of the cap. The heads are arranged to removably receive segmental rings 25 whose outer edges lie flush with the outer edges of the heads and whose inner 35 radius is greater than the bore of the cap. A number of rings having varying internal sizes are provided for use in each set of sleeves so as to provide for different depths of end fillets or flanges on the babbitt outwardly of the ends of the cap as clearly 40 shown in Fig. 2.

The sleeves at their opposite ends are provided with sockets 26 into which the adjacent ends of supporting rods 27 removably project, the sleeve being secured to the rods by wing screws 28. The rods are bent to form U-shaped yokes, extending away from the sleeves over the top and bottom of the plate 1 in suitable clearance relation thereto, and 45 then, toward each other back of said plate, passing through guide bosses 29 projecting from the plate. Between the bosses rigid arms 30 are secured to and project radially from the rods. Vertical link rods 31 pass 50 freely through the arms. The rods at their adjacent ends are connected to opposed crank arms 32 projecting from a transverse shaft 33, journaled on the member 2, and which is provided at its end opposite the handle 19 55 with a radial operating handle 34. A compression spring 35 disposed about each rod bears at one end against the corresponding arm 30 and at the other end against a collar 36 fixed on the rod at its outer end.

60 It will therefore be seen that a rotation of

the handle 34 in a direction to cause the upper link to be lowered and the lower link to be raised will cause the yokes 27 to be moved toward each other.

The sleeves 23 will then be slid along the 70 mandrel without compressing the springs 35 until the heads 24 abut against the cap 6. A further rotation of the handle will cause the springs to be compressed which will cause a firm pressure to be exerted to hold the sleeve 75 heads against the cap so as to form a tight joint. Owing to the use of the springs, caps of different lengths may be thus engaged by the sleeves with equal facility as will be evident. When the sleeves are thus positioned 80 and the cap clamped in place by manipulating the handle 19 as previously explained, the babbitt is poured into the space between the mandrel, cap and sleeves through an opening 85 37 provided in the upper one of said sleeves. The babbitt bearing 38 of the proper size throughout is thus immediately formed in connection with the cap, and since the mandrel has a smooth surface and is of the identical size as the shaft on which the cap is to be used, the bearing is then ready to be put into service without further treatment or finishing being necessary.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A babbetting jig for a bearing cap including a semicircular mandrel of the same diameter as the shaft with which the cap cooperates, a flat plate against which the mandrel and cap abut, means for rigidly securing the mandrel in a definite place on said plate, closure members for the ends of the cap slidably mounted on the mandrel, tapered nubs for engagement with the outer ends of the opposed bolt-holes of the cap, transversely extending pins from which said nubs project, means mounted in permanent relation with the plate for supporting said pins in a manner to enable the spacing between the nubs to be altered whereby to fit caps having different bolt-hole spacings, and means acting on said last named means for moving said nubs into frictional engagement with the metal about the bolt holes.

2. A babbetting jig for a bearing cap including a semicircular mandrel of the same diameter as the shaft with which the cap cooperates, a flat plate against which the mandrel and cap abut, means for rigidly securing

the mandrel in a definite place on said plate, closure members for the ends of the cap slidably mounted on the mandrel, tapered nubs for engagement with the outer ends of the opposed bolt-holes of the cap, transversely extending pins from which said nubs project, rods supporting said pins and slidably mounted in permanent connection with the plate, said rods being parallel to the nubs, and means mounted in connection with the plate for moving said rods longitudinally.

3. A device as in claim 2, in which said last named means comprises a cross bar connecting the rods, a rod slideable through the bar, a turnable crank-arm connected to one end of the arm, and a compression spring on said last named rod between the cross bar and crank.

4. A babbitting jig for a bearing cap including a mandrel of the same size as the shaft with which the cap normally cooperates, means for centralizing and securing a cap about the mandrel, closure members for the ends of the cap slideable along the mandrel, yokes connected to said members and mounted for sliding movement parallel to the mandrel, opposed arms projecting from the yokes, link-rods freely slideable through the arms and projecting toward each other, opposed crank arms to which the adjacent ends of the links are connected, means for rotating the crank arms as a unit, collars on the outer ends of the links, and compression springs between the collars and the corresponding arms.

5. A babbitting jig for a bearing cap including a mandrel of the same size as the shaft with which the cap normally cooperates, means for centralizing and securing a cap about the mandrel, closure members for the ends of the cap slideable along the mandrel, a pivoted lever, and flexible connecting units between said lever and the closure members arranged for moving the latter toward the cap and arranged to permit of variations in the extent of such movement with the same extent of movement of the lever.

In testimony whereof I affix my signature.
RAYMOND A. JOHNSON.
